TELEVISION TRANSMISSION

John V. L. Hogan, Forest Hills, N. Y., assignor
to Radio Inventions, Inc., New York, N. Y., a
corporation of New York

Application August 3, 1929, Serial No. 383,200

2 Claims. (Cl. 178—6)

The primary object of this invention is to make possible the transmission and reception of printed or written matter, and the like, by electrical methods including so-called "television". Other objects will appear from the following description.

In certain methods of electric picture transmission, the view to be transferred from sending to receiving point is scanned as a succession of 10 elemental areas, the number of such areas per view and the rate of their succession being varied within certain limits. The present invention is described with reference to its use in such a system, although it may be applied to other transmitting arrangements, e. g., those in which a plurality of channels are used for the concurrent transmission of two or more elementary areas.

A typical picture transmission involves the successive delivery, over a wire or radio communication channel, of impulses whose instantaneous value is proportional to the intensity of illumination or brightness of each given elementary area, beginning, for example, at the upper left and ending at the lower right of the view. If only a single picture is to be transmitted, one such series of impulses ordinarily suffices. If motion pictures or the effect of continuous vision is to be produced, the scanning process is repeated a fraction of a second later and, indeed, is substantially continuous, the successive views being scanned and transmitted sufficiently frequently to permit their recombination at the receiving point with the aid of the phenomenon of visual persistence in the eye or in the receiving apparatus or both.

The invention may best be understood by reference to the hereinafter specification and the drawings which constitute a part thereof, to wit:

Fig. 1 represents the field of view as composed 40 of a number of elemental areas.

Fig. 2 shows a human figure drawn in 21 elemental areas.

Fig. 3 shows the typical reproduction of a figure such as shown in Fig. 2 as received in a picture-transmission system.

Fig. 4 shows a human figure drawn in 192 elemental areas.

Fig. 5 shows the reception of a picture such as shown in Fig. 4 in a typical system.

Fig. 6 shows the heads of two different persons as received when 24 vertical elements are available for each.

Fig. 7 shows certain letters of the alphabet drawn on twelve vertical elements and as received on a 24 x 30 field.

Fig. 8 shows in plan and elevation an analogous method of transmitting a title or caption, according to my invention.

Fig. 9 shows a border used as a position datum.

Fig. 10 shows in diagrammatic form a simple 60 but typical radio "television" transmitting and receiving system.

Referring to Fig. 1, there is shown the normal field of such a transmission, divided into 720 elementary areas, as is the case when the view is scanned along 24 lines extending horizontally and displaced vertically and has a length to height ratio of 10/8. This is a common division in "television". It is obvious that no element of a view smaller than one of the elementary areas 70 shown can give a full black or full white impression in transmission, even though in itself it may be dead black or clear white. Consequently the detail of any view that can be transmitted is substantially limited by the number of elementary 75 areas, and in general details can be recognized at the receiving point only when they are of sufficient size to include substantially the whole of one or more such areas.

In many instances it is desirable to utilize substantially the entire vertical field in order to transmit the maximum amount of detail. For example, if portraits of a group of ten persons are to be transmitted it is obviously desirable that each portrait shall be shown with the greatest possible 80 definition in order that its identifying and individual characteristics shall be seen. If pictures of ten individuals were to be projected on a screen having only 30 elements in the horizontal direction it is obvious that only three elements would 85 be available for each of the ten individuals standing or sitting side by side. On the basis of normal proportions, from seven to ten vertical elements would be required for each human figure.

Figure 2 shows at A such a figure drawn within 95 the available area of 3 x 7 elemental areas from Fig. 1. Since detail corresponding to nothing smaller than a single elemental area can be transmitted, it is quite clear that the 21 areas available to each figure will not show enough 100 detail to make it recognizable—in fact—such a figure will be reproduced substantially as indicated in Fig. 3, and the group of ten standing persons would show as ten lateral repetitions of a pattern such as Fig. 3 side by side.

Even if the full twenty-four vertical elements are utilized for a single figure, only about eight will be used in the horizontal direction. Three figures can thus be distributed across the total field, but the detail of each will be extremely vague 110.

and evidently insufficient to transmit recognizable portraits. As indicated in Fig. 4 and Fig. 5, drawn on 8 x 24 elemental areas and having the same relation as Figs. 2 and 3, all three human figures will look substantially alike and only the most striking differences will permit differentiation.

On the other hand, if the full field vertically is used for a head it becomes possible to show enough detail of the features to permit some degree of personal identification. The two heads shown on 24 vertical elements in Fig. 6 are obviously recognizable as pictures of two different persons.

15 The same difficulty of transmitting adequate detail to permit recognition appears when one attempts to transfer printed or written copy in a field of relatively small total number of elemental areas. For the sake of illustration we may consider the minimum number of elements that will permit easy recognition of the simplest block-form of capital letters.

Fig. 7 shows the letters A, B, C, and G, with 12 vertical elements. It is clear that with less than 12 vertical elements the identity of various letters is quite uncertain, and that the use of even more than 12 is desirable. With twelve vertical elements from 2 to 12 horizontal elements are required per letter, and consequently not more than two to four letters can be shown simultaneously on a 24 x 30 field, as is shown by this figure.

If the number of elements in the field is increased the same difficulty exists, though to a lesser degree. With 48 x 60 field it becomes possible to show from 4 to 8 letters simultaneously or to transmit a single short word. With 60 x 72 field, a word of 6 to 10 letters can be transmitted. With 120 x 144 a short group of words can be shown always assuming that the detail of these relatively finely-divided fields is accurately transmitted so that each elemental area is given its proper light-intensity value. As is well known, such fidelity of transmission is exceedingly difficult of attainment.

45 From the above it is evident that with the present limitations of "television" it is extremely difficult if not impossible to transmit a recognizable picture of more than two individuals or a title comprising more than two or three short 50 words. In the absence of any method of overcoming this difficulty it has been proposed that the portraits of a group of individuals be transmitted individually and successively, or that the words of a title be transmitted by spelling them out one letter or one short word at a time.

Such methods of transmission lack the element of continuity and show no relationship between the successively transmitted images, and have proved unsatisfactory.

60 According to my invention, I transmit as much of the total view as can be clearly seen in the field of the apparatus and then move the field of view progressively and preferably uniformly so that the whole view is transmitted without any 65 break that would mar its continuity and the relationship of its parts.

According to one way of practicing my invention, a long title or sentence for "television" transmission may be prepared by printing it upon a 70 paper strip which is passed before a motion-picture copying camera at such distance that the letters occupy preferably at least $\frac{1}{3}$ to $\frac{1}{2}$ of the vertical dimension of the field, as shown in Fig. 8.

When a film so made is passed through a "television" system, the receiver will reproduce the

text as though the observer's eye were passing along the printed line, and by reason of the large and clear lettering used and the continuity of motion the text is easily read without much regard to its total length.

It is possible to dispense with the intermediate step of making a motion picture film of each view or printed strip to be transmitted if the television transmitted is of such character that the objects or letters to be transmitted can be caused to pass across its field of view by suitable relative motion.

85 Turning to the "television" receiving apparatus, it should be noted that any lack of exact synchronism between sender and receiver will cause the image at the receiver to appear to float out of the field of view, usually either to the right or left. In operating such receiving apparatus it is customary to adjust the speed of the receiving scanning device so that the images remain centered in the field of view of the receiver. Consequently a receiving operator who intercepts such moving images (whether of persons, letters or objects) as have just been described, may attempt to hold them stationary by changing the speed of his scanning mechanism.

Such adjustment of the receiver would destroy synchronism between sender and receiver and produce unsatisfactory results. I therefore prefer to provide in each such view a fixed datum point or mark which will indicate a position past which the objects or letters are moved, and which may be held in position by either the manual or automatic synchronism control of the receiving apparatus.

Such datum may take the form, for example, of a frame or border (Fig. 9), a pair of vertical bars at each side of the view, one or more dots or figures, etc. This datum or index provides a convenient check on the speed adjustment of the receiving scanner.

A complete "television" radio system adapted for use of panoramic film such as described is illustrated in Fig. 10. The prepared film passes with the customary intermittent motion from reel A to reel B. For the fraction of a second required to scan one frame of the film it remains stationary between the lenses D and E, light from the lamp C passing through the orifices (spirally arranged as usual) in the rotating scanning disc K driven by motor M. The light passing through each scanning hole falls upon the photoelectric cell F, giving rise to electrical impulses which are amplified at G and caused to modulate the continuous radio frequency current generated by the radio transmitter H. These picture-modulated currents impressed on the antenna-ground system I—J result in the radiation of radio waves carrying the picture modulation.

At the receiver the waves are intercepted by the antenna-ground system MN and the resulting currents selected, amplified and rectified by the radio receiver O. They may be further amplified at P and are then impressed upon a glow lamp or other variable-intensity light source at Q. A synchronous scanning disc R of the usual type is driven by motor C and light passing through its orifices from D is seen by the eye of the observer at T. The picture originally scanned at the transmitter is thus reconstructed at the receiver.

It will be understood that the system I have described for the purpose of overcoming certain difficulties imposed by the limitation of detail that can be transmitted by "television" is applicable whether used to reproduce silhouette or half tone drawings, photographs, views or letters.

Many variations of the general system may be

- utilized, e. g., titles or sketches may be shown in the act of being lettered or drawn upon the field of view (preferably toward one side thereof) and streaming off out of sight as they are completed. 5 Moreover, although I have described the invention in relation to a system involving essentially square picture elements, the improvement is useful with circular, rectangular or other forms of elementary area.
- 10 The present invention is to be distinguished from so-called "talking signs" which are specifically for the purpose of exhibiting long sentences or groups of words by electric lights automatically switched to produce an illusion of motion. No 15 space limitations are involved, nor is there any limitation as to the amount of detail that can be shown (i. e., the number of lamps allotted to each letter). Similarly, the present invention is to be distinguished from motion-picture projection 20 upon the screen of panoramic landscapes and the like. In motion-picture projection there is no lack of detail and the only purpose of moving the camera is to include more of the view than could be seen by the human eye (or recorded by the 25 camera lens) in a single position. In contrast to both of these, "television" transmission is so limited in picture detail that in many instances the images received cannot be recognized unless by some method the observer is told what to look 30 for. Even under the best transmission conditions I have found that a vastly better appreciation of the transmitted pictures can be given to the observer if explanatory notes and titles are freely interspersed with the pictures.
- 35 These notes may be prepared and transmitted as explained above in connection with Figs. 8 and 9, just as are the pictures of other subjects, and the same rules apply as to the necessity of including sufficient vertical and horizontal elements 40 to provide adequate detail.
- Variations in the design and condition of adjustment of the apparatus and of the condition of the transmitting medium often result in distortion which tends to destroy the identity of the 45 image. It is therefore desirable to use as many vertical elements as possible so as to produce a maximum clarity in the reproduction.
- It should be borne in mind that the amount of detail in the transmitted picture is a function of 50 the number of elements into which it is divided rather than the magnification of the image. Present practice would suggest a minimum limit of say 24 by 30 and a maximum of about 160 by 200 and an intermediate range of about 48 by 60 55 as desirable under various conditions.
- For simplicity in illustration I have omitted half tone effects and limited the drawings of transmitted images to black and white. The principle exemplified, however, is applicable to 60 all gradations within the scope of the instrumentalities available.
- By this system it will be understood that it is desired to transmit from one point to another an image of a subject. This is done by sending 65 successive views of parts of the subject, which views are reconstructed into the desired final image or duplicate representation of the subject.
- The image of course is what the observer sees. By this method I reproduce in effect panoramic 70 or other pictures with what may be termed "running" titles which titles may be of indefinite length and consist of letters of sufficient size to be readily distinguished so that unlimited explanatory facility is provided.
- 75 Because of the fact that the television system described utilizes the phenomenon of optical persistence to give the illusion of continuous vision in spite of the transmission of separate views taken at short intervals of time, the displacement of the subject in the field of view must not be too great between any one view and the next. Otherwise the result will be confusing to the observer, producing the appearance of too rapid motion or even of overlapping images. In transmitting a line of text at the rate of 15 views per second, 80 I have obtained excellent results by adjusting the speed of lateral motion from left to right so that any given letter appeared to cross the full field of view from right to left (i. e., the field of view appeared to cross that letter in the direction of normal reading, from left to right) in from 1.5 to 3.5 seconds. This does not represent the useful limits of such motion, since either faster or slower translation may be utilized so long as on the one hand the impression does not become confused nor, on the other, the time available for transmitting the entire subject is not exceeded. In the above instance the vertical dimension of each letter was about $\frac{1}{4}$ of the total height of the field of view, and from four to six letters or equivalent characters or spaces appeared across the field at the same time. 85
- By increasing the number of views per second the time rate of motion may be increased without confusion. When smaller letters are used, 90 so that more appear in the field at the same time, the time rate of motion should be decreased. In television it is customary to transmit from 7 to 20 views per second, or thereabout, and with characters occupying a substantial fraction of the 95 vertical dimension of the field of view it is desirable to adjust the motion so that the displacement between one view and the next is not much greater than 1/20th of the dimension in the direction of motion, so that the same character or 100 object (or some part of it) will remain visible during the time of at least 20 views. I have had good results with the motion adjusted so that part or all of a single object remained in sight 105 during the time of about 60 successive views. 110
- In the claims the use of the terms "subject" and "object" is intended to apply broadly to all animate and/or inanimate bodies and/or to one or more letters or words as they may appear in the views to be transmitted. 115
- I claim:
1. In a system of electrical transmission of images of a writing, the combination of means at the transmitter for analyzing the subject into successive views each consisting of elemental areas, a carrying film having successive views of parts of said writing, said views being disposed at substantially equal intervals along said film and each letter of said writing occupying more than one-third of one dimension of said 120 view, successive views being progressively displaced laterally at substantially uniform increments of distance from a margin of the film, means controlled by the film for producing electrical impulses corresponding in intensity to the 125 optical values of the elemental areas of the views carried by said film, means for conveying said impulses to a receiver and means at the receiver for synthesizing and observing whereby the observed image appears to move at a substantially 130 uniform velocity across the line of vision so that said writing shall be reproduced in the proper temporal and spacial sequence.
  2. In a system of electrical transmission of images of text characters, the combination of 135

means at the transmitter for analyzing the subject into elemental areas, a record carrying said text characters and adapted to be moved in the direction of the normal succession of said characters, each character occupying more than one-third of the narrower dimension of the field of scanning, means for moving said record continuously in one direction so as to display said characters in their normal sequence, means controlled by said record for producing electrical

15 means for receiving and analyzing the signals from the transmitter, means for conveying the signals to a receiver and means for synthesizing and observing whereby the observed image appears to move at a substantially uniform velocity across the line of vision so that

20 said characters shall be reproduced in the proper temporal and spacial sequence.
